US0D1055259S

(12) **United States Design Patent** (10) **Patent No.:** **US D1,055,259 S**
(45) **Date of Patent:** **** Dec. 24, 2024**

(54) **DESKTOP FAN**

(71) Applicant: **Shenzhen Huachuang Shangpin Technology Co., Ltd.**, Guangdong (CN)

(72) Inventor: **Peihua Wang**, Guangdong (CN)

(***) Term: **15 Years**

(21) Appl. No.: **29/924,148**

(22) Filed: **Jan. 17, 2024**

(51) LOC (14) Cl. **23-04**

(52) U.S. Cl.

USPC **D23/370**

(58) **Field of Classification Search**

USPC D23/332, 355, 370, 381

CPC F04D 25/105

(57) **CLAIM**

The ornamental design for a desktop fan, as shown and described.

DESCRIPTION

FIG. 1 is a perspective view of a desktop fan showing my new design.

FIG. 2 is a front view thereof.

FIG. 3 is a rear view thereof.

FIG. 4 is a left side view thereof.

FIG. 5 is a right side view thereof.

FIG. 6 is a top view thereof.

FIG. 7 is a bottom view thereof; and,

FIG. 8 is a rear, bottom perspective view thereof.

The broken lines in the drawings depict portions of the desktop fan that form no part of the claimed design.

1 Claim, 8 Drawing Sheets
